ATTORNEY'S

UNITED STATES PATENT OFFICE.

WILLIAM J. NOONAN, OF MANSFIELD, MASSACHUSETTS.

ELECTRIC SWITCH MECHANISM.

Original application filed May 31, 1924, Serial No. 716,866, now Patent No. 1,528,300, dated March 3, 1925. Divided and this application filed January 23, 1925. Serial No. 4,167.

This application is a division of an ap-part switch lever pivoted at 12. One member of the switch lever is shown at 14 and the other member at 15. The member 14 consists of a strip of spring metal, preferably brass, having an insulated handle 11. The member 15 is also of spring metal and is mounted on the member 14. Said members 14 and 15 are pivotally secured to an insulation base 16 by the headed pin 12 which passes through both members 14, 15. The arm of said switch member 14 which is on the handle side of the pivot slides on a rest bar 13 which is preferably arc-shaped. The said bar 13 is formed with a series of humps 17 spaced slightly apart from each other forming notches between them, and the switch member 14 is formed with a hump 18 on its underside which is adapted to engage in the notches between the humps 17 of the rest bar 13 to hold the switch in its adjusted position when the member 14 is in contact with one of the contact pins 30, 31, 32, 33, 34, 35, 36 hereinafter described.

When a single lever is employed to close two different circuits simultaneously through different contact points with which different parts of the lever engage, the tension at the two different contact points is usually unequal so that if adjusted to make the proper tension at one contact the tension will be either too slight or too great at the other contact and result in poor connection in one of the circuits. The object of the present invention is to provide a switch lever which can be set so as to close or open as the case may be two different electrical circuits simultaneously and to provide independent tension for each contact member of the switch, each of which may be given the tension desired.

The invention will be fully understood from the following description when taken in connection with the accompanying drawings and the novel features thereof will be pointed out and clearly defined in the claims at the close of this specification.

In the drawings:

Fig. 1 is a plan view showing switch mechanism embodying the invention and showing in diagram two electric circuits with which said switch mechanism is connected.

Fig. 2 is a detail plan view of the switch lever on an enlarged scale from that shown in Fig. 1.

Fig. 3 is a sectional view through the switch base and lever.

Fig. 4 is a plan view, partly in diagram, showing a modified form of switch mechanism, the electric circuits being shown in diagram.

Fig. 5 is a plan view of the switch lever shown in Fig. 4.

Fig. 6 is a sectional view through the switch base and lever of Fig. 4.

Referring to the drawings:

There is shown at 1 an electric motor. At 4 is shown a heating coil and 5, 51 and 52 a plurality of resistance coils in series with the motor. At 6 is represented the positive wire and at 7 the negative wire of an electric circuit. Preferably the switch lever is a two-part lever. In the drawings it is shown as a two-part lever as follows:

At 11 is shown the handle of a two-

part switch lever pivoted at 12. One member of the switch lever is shown at 14 and the other member at 15. The member 14 consists of a strip of spring metal, preferably brass, having an insulated handle 11. The member 15 is also of spring metal and is mounted on the member 14. Said members 14 and 15 are pivotally secured to an insulation base 16 by the headed pin 12 which passes through both members 14, 15. The arm of said switch member 14 which is on the handle side of the pivot slides on a rest bar 13 which is preferably arc-shaped. The said bar 13 is formed with a series of humps 17 spaced slightly apart from each other forming notches between them, and the switch member 14 is formed with a hump 18 on its underside which is adapted to engage in the notches between the humps 17 of the rest bar 13 to hold the switch in its adjusted position when the member 14 is in contact with one of the contact pins 30, 31, 32, 33, 34, 35, 36 hereinafter described.

As the switch lever 14 is held down at the pivot point by the head of the pivot pin 12 that arm of the lever 14 which bears on the rest bar 13 has to be sprung up slightly to bring it onto the upper side of the rest bar 13 so that it will bear on the contact pins hereinafter described. The switch lever is thus maintained under tension where it engages the contact pins.

The arm 14^a of the switch member 14 on the opposite side of the pivot from the rest bar 13 rides on a contact strip 19 secured to the insulation base 16. The arm 14^a is formed with a slot 14^b and the superposed switch member 15 is formed with a bent tongue 15^a which extends down through the said slot to form a contact with the contact pins 37, 38 to be hereinafter described. Said member 15 is of spring metal and its free end is put under tension when it is sprung up as by riding over the convex heads of the contact pins, thus giving the tension to the arm 15 independent of the tension of the arms 14^a or 14.

One example of the way in which the improved switch may be used is as follows:

The positive leading-in wire 6 of the main line is in electrical connection with the positive contact bar 19 through a binding post at 21. The negative leading-in wire 7 is connected with the insulated base 16 by a binding post at 22. A branch 71 from the

negative wire 7 leads to the motor 1. A branch 72 from the negative wire 7 leads to the heating coil 4.

The switch member 14 is in contact with the positive contact strip 19 and therefore with the leading-in wire 6 in all of the adjusted positions of the switch lever. A positive wire 61 leading to the motor is adapted to be electrically connected with the positive leading-in wire 6 through the contact strip 19, switch arm 14 and the contact pin 30 so that when the switch lever is moved over to engage with pin 30 the circuit may be made through the motor without passing through any of the resistance coils 5, 51, 52 or through the heating coils.

The contact pins 31, 32 have respectively electric connection through the wires 63, 64 with the resistance coils 5, 51 respectively.

An insulated projection 33 is provided as a seat for the switch lever to maintain it in neutral position when desired.

When the switch is in contact with any one of the pins 32, 31 or 30 or any other contact on that side of the neutral 33, the arm 15 is entirely out of electrical contact with any of the contact members which close the circuit through the heating coil and is therefore inoperative. A plurality of contact pins 34, 35 and 36 are provided on the opposite side of the neutral from the pins 30, 31, 32 for making connection through the switch with the heating coils.

A plurality of contact pins 37, 38 are provided with which the tongue 15^a of the switch arm 15 is adapted to engage respectively when the switch lever is turned to bring that portion of the arm 14 which is on the handle side of the pivot into engagement with one of the pins 34, 35.

The pin 37 is electrically connected by wire 65 with the resistance coil 51, by intermediate connection with wire 64 which leads from contact pin 32. Contact pin 38 is electrically connected by wire 66 with the resistance coil 52.

When the switch lever is turned to bring the main switch arm 14 into contact with the pin 34, the tongue 15^a of the arm 15 will simultaneously contact with pin 37. The positive connection with the motor will then be made through the wire 61 contact strip 19, switch arm 15, tongue 15^a, contact 37, wires 65 and 64, resistance coils 51 and 5 and wire 61.

At the same time the circuit through the heating coil will be closed by the arm 14, pin 34, and wire 62.

When the switch is turned further over to bring the arm 14 into contact with pin 35, the tongue 15^a will engage pin 38 and the circuit to the motor will be closed through the wire 63, the resistance coils 52, 51 and 5 and wire 61.

When the switch is moved over another

point to the pin 36, the furthest on that side of the neutral, the tongue 15^a at the opposite end of the switch will have moved out of contact with the pin 38 and entirely out of connection with any of the wires leading to the motor so that the circuit through the motor will be broken but the circuit through the heating coil will remain closed.

In the modified form shown in Figs. 4, 5 and 6 there are three heating coils 4, 4^a and 4^b, the coil 4 being in the circuit formed in part by the negative wire 72 and the positive wire 62 as previously described. The heating coils 4^a and 4^b are in series with each other and are connected by wire 72 with the leading-in negative wire 7 and are connected with the positive contact wires 35 and 36 by the wire 67. The contact members 35 and 36 are in series with each other as described in connection with the device shown in Fig. 1, but they are not in series with the contact member 34. Contact members 38 and 37 are electrically connected with the resistance coils 52 and 51 respectively by the wires 66 and 64 previously described with reference to Fig. 1. The resistance coil 5 is connected with contact member 39 by wire 62, the said contact member 39 being in series with contact member 31.

In this modified form the contact members 38, 37 and 39 are disposed on the base 16 on the opposite side of the pivot 12 from the arrangement of the contacts 38 and 37, shown in Fig. 1. In order, therefore, for the switch arm 15 to make a contact with members 38, 37 and 39, said switch arm 15 is provided with a tongue 15^b under tension similar to the tongue 15^a and said tongue 15^b extends down through a slot 14^c in the arm 14 and is adapted to engage under tension with the contact members 38, 37 and 39 in the several adjusted positions of the switch.

When the switch lever is moved over to make contact with member 38 the arm 14 on the handle side of the pivot will make contact with member 34, the further arm of said lever being as previously described always in engagement with the contact bar 19. In this position of the switch, the tongue 15^b will be in engagement with contact member 38. The engagement of the switch with the contact member 34 will close the circuit through the wire 62 and heating coil 4. At the same time the engagement of the tongue 15^b with contact member 38 will close the circuit through the resistance coil 52.

When the switch is moved over to the second station on that same side of neutral, the switch tongue 15^b will engage with the contact member 37 to close the circuit through the wire 64 and resistance coil 51. At the same time the switch arm 14 will engage with contact member 35 and close the circuit through the wire 67 and the two

heating coils 4^a and 4^b and will cut out the heating coil 4. When the switch is moved over to the third station, the tongue 15^b will engage with contact member 39 and close the circuit through the wire 63 and the resistance coil 5 cutting out the resistance coils 51 and 52. 5

A contact pin 68 is mounted on the base 16 in position to be engaged by the switch 10 tongue 15^a when the switch is at the third station and a wire 69 leads from said contact member 68 and is tapped onto the wire 62 leading to the heating coil 4. Thus when the switch is at the third station the three 15 heating coils 4, 4^a and 4^b will be operative and the resistance coil 5 is the only resistance left in the motor circuit.

While I have shown and described two different systems in which a switch mechanism embodying my invention may be employed, I wish it to be understood that the claims are intended to cover switch mechanism embodying the invention, regardless of the particular form of apparatus in which it 25 is employed.

What I claim is:

1. A switch lever comprising two resilient contact members one of which is superimposed upon the other in the same longitudinal direction, a supporting base on which said two members are pivoted intermediate their ends, a pivot for said two members, said two contact members being connected in such a manner that they turn as one on said pivot, two sets of contact elements with which said switch members are respectively adapted to simultaneously engage to close two separate circuits, each of said contact members of the switch having 40 its own tension independent of the other.

2. A switch lever comprising two resilient contact members one of which is superimposed upon the other and parallel therewith, a supporting base on which said two 45 members are pivoted intermediate their

ends, a pivot for said two members, said two contact members being connected in such a manner that they turn as one on said pivot, one of said switch members being formed with a slot and the other member having a projection which extends through the said slot and is adapted to form a contact with an underlying contact member. 50

3. A switch lever composed of two resilient members each of which is adapted to make electric contact, one of said members being superimposed upon the other and being in electric contact therewith and extending in the same longitudinal direction, a common pivot for said two members intermediate their ends, said members being secured together in such a manner that they turn as one on said pivot, said contact members being adapted to respectively engage under tension contact members in different 60 circuits in such a manner that the tension of each switch contact member is independent of the tension of the other switch contact member. 65

4. A switch lever composed of two resilient members each of which is adapted to make electric contact, one of said members being superimposed upon the other and being in electric contact therewith and extending in the same longitudinal direction, a common pivot for said two members intermediate their ends, said members being secured together in such a manner that they turn as one on said pivot, two sets of contact elements in different circuits with which 75 said switch members on one side of said pivot are respectively adapted to engage simultaneously and another set of contact elements with which one of the switch members on the opposite side of the pivot is 80 adapted to engage. 85

In testimony whereof I affix my signature.

WILLIAM J. NOONAN.
